[57] CLAIM

The ornamental design for a double-action fishing hook,
as shown and described.

DESCRIPTION

FIG. 1 is a front elevational view of a double-action fishing hook according to the present invention.

FIG. 2 is a left side elevational view of the fishing hook of FIG. 1.

FIG. 3 is a top plan view of the fishing hook of FIG. 1.

FIG. 4 is a bottom plan view of the fishing hook of FIG. 3, where the hook of FIG. 3 is rotated to the right of FIG. 3 through an angle of 180 degrees.

FIG. 1

FIG. 2

FIG. 3

FIG. 4
